(57) **CLAIM**

The ornamental design for an electric spin scrubber, as shown and described.

DESCRIPTION

FIG. 1 is a front perspective view of an electric spin scrubber, showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is an enlarged view thereof, taken from portion 8 in FIG. 1;

FIG. 9 is an enlarged view thereof, taken from portion 9 in FIG. 1; and,

FIG. 10 is an enlarged view thereof, taken from portion 10 in FIG. 1.

The dash-dash broken lines in the drawings illustrate the portions of the electric spin scrubber, which form no part of the claimed design. The dot-dash broken lines illustrate the bounds of the portions of the drawing figures from which the enlargements were extracted, as well as to illustrate the bounds of the enlarged views; the boundaries form no part of the claimed design.
